UNITED STATES PATENT OFFICE.

CHARLES A. DUEPNER, OF MINNEAPOLIS, MINNESOTA.

DESIGN FOR A LIGHTING-FIXTURE.

56,742.

Specification for Design.

Patented Dec. 14, 1920.

Application filed December 30, 1918. Serial No. 268,997. Term of patent 14 years.

To all whom it may concern:

Be it known that I, CHARLES A. DUEPNER, a citizen of the United States, residing at Minneapolis, in the county of Hennepin and State of Minnesota, have invented a new, original, and ornamental Design for a Lighting-Fixture, of which the following is a specification, reference being had to the accompanying drawing, forming part thereof.

The figure shows a side elevation view of

my design, the canopy or supporting means being of metal, and the reflector being of the conformation shown in the drawing, the reflector thereof being composed of transparent glass and the bowl being composed of an opaque material, preferably glass.

I claim:

The ornamental design for a lighting fixture, as shown.

CHARLES A. DUEPNER.
